UNITED STATES PATENT OFFICE.

JOHN ROUGE, OF NEW YORK, N. Y.

AIR-BRUSH.

1,270,553.

Specification of Letters Patent. Patented June 25, 1918.

Application filed March 16, 1918. Serial No. 222,883.

To all whom it may concern:

Be it known that I, Dr. JOHN ROUGE, a citizen of the United States, residing at New York, in the county of New York and State 5 of New York, have invented certain new and useful Improvements in Air-Brushes, of which the following is a specification.

This invention relates to air brushes, and more especially its object is to provide the 10 same with a removable and adjustable cup containing a number of cells for the storage of color, whereby the brush may be used to apply one color and then the cup changed in position so that the brush will apply another color.

Other objects are brought out by the following specification, and reference is made to the drawings, wherein:—

Figure 1 is a plan view of an air brush 20 with this improvement applied.

Fig. 2 is a side elevation thereof, and

Fig. 3 is an enlarged transverse vertical section through the improvement or attachment alone.

25 For purposes of reference only I will state that the air brush herein shown comprises the usual handle H tapering to a tip T at its front end, A is the air inlet, N is the nipple to which the color cup is ordinarily attached, 30 and C is the control. In the present case I remove the color cup and apply the parts now to be described.

The numeral 1 designates a substantially horizontal support having at one extremity 35 a claw 2 intended to be passed over and astride the nipple N, and the numeral 3 designates a collar intended to slide on the support and draw the arms of the claw together more tightly around the nipple to 40 hold the support thereon. The outer end of the latter passes through an opening 4 in the upper end or head of a pivot post 5, which head 6 is slightly enlarged as best seen in Fig. 3 and for a purpose yet to appear, and a set screw 7 passes downward 45 into said head and engages the support 1 to hold the post in adjusted positions thereon or to permit the post to be removed therefrom when desired.

50 Instead of a single color cup I use one employing a plurality of cells numbered 10 in Fig. 1, and as these cells are duplicates of each other the description of one will suffice for all. They are revolvably supported upon the head 6 of the post 5, and 55 collectively they constitute the cup which

will rotate around said post when no cell or its outlet nozzle engages the air brush head. Each cell 10 contains a tube 11 extending obliquely upward along the outer 60 side of the cell and turned outward into a nozzle 12, its lower end being by preference closed by a removable plug 13 which may be withdrawn for cleaning out the tube from time to time; and the body of the tube just 65 above this plug has an inlet port 14 into which the color or pigment within the cell enters the tube when suction is set up in the latter. Obviously the tip of the nozzle 12 is intended to be projected into the nipple 70 N when any particular cell is disposed next to the air brush structure, and at this time the cup as a whole is moved toward said structure and the head slid along the support, so that the final setting up of the set 75 screw 7 holds all parts in assembled position. The air brush may now be used as ordinarily employed, controlled by pressure of the finger at the point C as usual, and whatever color is within the cell which is connected 80 with the nipple to be projected at the tip T in a manner well understood. As soon as the operator desires to use another color, he has but to loosen the set screw 7, slide the head 6 outward on the support 1, revolve the 85 cup until the proper cell comes opposite the nipple, and then restore the parts to the position shown and described. It is not necessary that he shall have different colors in 90 the several cells, as he may have them all 95 full of one color if preferred, or in fact he may use the attachment as he pleases. I do not wish to be limited to the details of construction, and the materials and proportions of parts are not necessary to this specification.

What is claimed as new is:—

1. An air brush attachment comprising a support having at one end means for fastening it to the handle of the air brush, an upright post pierced with a transverse opening 100 adjustably mounted on the other end of said support, and a cellular cup rotatably mounted on the post beneath said support, for the purpose set forth.

105 2. An air brush attachment comprising a support having a claw at one end, a collar slidably mounted on the support for passing the arms of the claw toward each other, an upright post having a head pierced with 110 a transverse opening slidably mounted on the other end of said support, a set screw

in said head intersecting said opening, and a cellular cup rotatably mounted on the head of the post beneath said support, for the purpose set forth.

5. 3. An air brush attachment comprising a support adapted to be engaged with the inlet nipple of the brush, an upright post adjustably mounted on the outer end of the support, a cellular cup rotatably mounted 10 around said post beneath the support, and an outlet nozzle in each cell adapted selectively to be projected into said nipple when the attachment is applied to an air brush.

4. In an air brush attachment, the combination with a cellular color cup, an outlet tube in each cell thereof having a radially projecting nozzle at its upper end and an inlet port near its lower end, and a plug removably closing its lower extremity; of an 15 upright post on which said cup is rotatably mounted, and means for supporting the post 20 from the air brush structure.

5. In an air brush attachment, the combination with a cellular color cup, an outlet tube in each cell thereof having a radially 25 projecting nozzle at its upper end and an inlet port near its lower end, and a plug removably closing its lower extremity; of an upright post at the axial center of the cup and having an enlarged head on which said 30 cup is rotatably mounted; the head being provided with a transverse opening and having an upright opening intersecting the same, a set screw in the last-named opening, and a support in the transverse opening 35 under the set screw and extending over the cup and radially thereof, for the purpose set forth.

In testimony whereof I affix my signature in presence of two witnesses.

DR. JOHN ROUGE.
